LAMPHOUSING FOR A PHOTOGRAPHIC ENLARGER

Alfred Simmon, Garden City, N.Y., assignor to Simmon
Brothers, Inc., Long Island City, N.Y., a corporation
of New York

Filed Apr. 11, 1960, Ser. No. 60,114

Term of patent 14 years

(Cl. D61—1)

Fig. 1.

Fig. 2.

Fig. 3.

Figure 1 is a front perspective view of the lamphousing for a photographic enlarger of the present invention;
Fig. 2 is a rear perspective view; and
Fig. 3 is a side elevational view thereof.

I claim:

The ornamental design for a lamphousing for a photographic enlarger, as shown.
